AUTOMATIC CHUCKING MACHINE

Robert Djidich, Chicago, Ill., assignor to Robert Djidich
Machine Products Corporation, Chicago, Ill., a corpora-
tion of Illinois

Application April 7, 1955, Serial No. 35,395

Term of patent 14 years

(Cl. D54—14)

FIG. 2

FIG. 1
2

Figure 1 is a front elevational view of an automatic chucking machine showing my new design.

Fig. 2 is a side elevational view, looking along the lines 2—2 of Fig. 1.

The side opposite to that shown in Fig. 2 is substantially like the side shown except that its external walls are without the plates, etc., shown in the lower central portion of said Fig. 2.

I claim:

The ornamental design for an automatic chucking ma-
chine, as shown and described.
